CLAIM

The ornamental design for a side release buckle, as shown and described herein.

DESCRIPTION

FIG. 1 is a perspective view of a female component of a side release buckle showing the new design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a first end elevational view thereof; and

FIG. 7 is a second end elevational view thereof;

FIG. 8 is a perspective view of a male component of a side release buckle showing the new design;

FIG. 9 is a bottom plan view thereof;

FIG. 10 is a top plan view thereof;

FIG. 11 is a left side elevational view thereof;

FIG. 12 is a right side elevational view thereof;

FIG. 13 is a first end elevational view thereof; and

FIG. 14 is a second end elevational view thereof;

FIG. 15 is a perspective view of a side release buckle including the female and male components of FIGS. 1-14 showing the new design;

FIG. 16 is a top plan view thereof;

FIG. 17 is a bottom plan view thereof;

FIG. 18 is a right side elevational view thereof;

FIG. 19 is a left side elevational view thereof;

FIG. 20 is a first end elevational view thereof; and,

FIG. 21 is a second end elevational view thereof.

The broken line portions of the disclosure are for illustrative purposes only and form no part of the claimed design.
